CLAIM

The ornamental design for lighter, as shown and described.

DESCRIPTION

FIG. 1 is a perspective view of a lighter showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is an enlarged view of FIG. 6; and,

FIG. 9 is an enlarged view of FIG. 7.

The broken lines depict portions of the lighter and form no part of the claimed design.
